UNITED STATES PATENT OFFICE.

JOHN MURRAY, OF LONDON, ENGLAND.

BOOKBINDING MACHINERY.

1,410,498.

Specification of Letters Patent. Patented Mar. 21, 1922.

Application filed February 25, 1921. Serial No. 447,687.

To all whom it may concern:

Be it known that I, JOHN MURRAY, a subject of the King of Great Britain and Ireland, and a resident of London, England, 5 engineer, have invented certain new and useful Improvements in Connection with Bookbinding Machinery, of which the following is the specification.

The invention relates to machines for affixing covers to books—usually known as “casing-in” machines and in which adhesive is distributed upon the sides of the books previously to the application of the covers to them.

15 Hitherto, a difficulty in this operation has been to ensure that there should be sufficient adhesive about those slightly projecting edges adjacent to the back to ensure that the longitudinal grooves or folds in the 20 cover at these points at each side of the back should be adequately secured. The invention has for its object simple and effective means for the distribution of adhesive whereby these disabilities are overcome.

25 According to the invention there is provided an adhesive-applying roller of length and diameter commensurate with the dimensions of the book and having in it a longitudinal groove of a transverse contour 30 substantially conforming to that projecting edge of the book the application of adhesive to which is particularly essential. With this roller there coacts a ductor roller of like dimensions arranged adjacent and with 35 its axis parallel. Upon the ductor roller is a longitudinal rib in contour substantially a counterpart to the longitudinal groove in the adhesive-applying roller. The two rollers are geared together so that the rib coacts 40 with the groove during their revolution after the manner of the well-known “Geneva” movement. Preferably, the rib is slightly narrower than the groove, and means may be provided for fine relative adjustment of the 45 rollers, so that the rib may be set either centrally to the groove, or more adjacent to one side or the other. This adjustment renders it possible to determine the volume of adhesive gathered between the side of the 50 groove and the side of the rib and so the amount which is distributed upon the projecting edge of the book.

Adhesive may be supplied to the rollers in any convenient manner—for example, by 55 a series of ductor rollers from a trough.

The rollers may be pressed towards one

another by springs or other means, and cam or other devices may be provided for varying their contiguity during their operation and thus varying the thickness at different points of the layer of the adhesive they convey to the books.

Either the adhesive-carrying roller may be applied to the book, or the book may be applied to the adhesive-carrying roller. In either case a stop device is preferably applied to limit the travel of the roller definitely so that it may not overrun the open edge of the book.

In addition to the ductor roller, other ductor rollers, scraping devices, or means for controlling the supply of adhesive to the adhesive-applying roller may be provided.

Sufficient of a casing-in machine embodying the features which form the subject of the present invention to diagrammatically illustrate an example of its carrying out is shown on two accompanying sheets of explanatory drawings, Figures 1 and 2 being elevations at right angles to one another and showing the devices for applying adhesive to one side of a book, like devices being provided to operate upon the other side of the book.

The book A is presented upon a blade A¹ which is raised and lowered in a vertical plane in consonance with the motions of the gluing mechanism by any form of cam or equivalent mechanism (not shown) to an adhesive-applying roller B of length and diameter commensurate with the dimensions of the book and having in it a longitudinal groove B¹ substantially conforming to the projecting edge A² of the back of the book. A. With this roller B there coacts a ductor roller C having a longitudinal rib C¹ counterpart to the groove B¹. The ductor roller C is fed with adhesive from a trough D¹ by a second and again counterpartly grooved 100 ductor roller D.

The adhesive-applying roller B is mounted on arms B² which are pivoted on a shaft B³. These arms are connected by links B⁴ to levers B⁵ fast on a rocking shaft B⁶ fast 105 on which is also a quadrant B⁷ gearing with a rack-bar B⁸. This rack bar is operated by a cam or equivalent (not shown) in consonance with the means for raising and lowering the book, and by it and the link 110 connections the arms B² are caused to alternately advance the roller B to the book and

apply adhesive thereto (the book meanwhile moving past the roller) and retire the roller B into contact with the ductor roller C, as indicated by chain lines, to receive a supply 5 of adhesive therefrom.

Upon the spindle of the roller B is a helical gear wheel E gearing with a like wheel E¹ on a spindle E² carried in brackets E³ in one of the arms B² and having at its 10 lower end a helical gear wheel E⁴ gearing with a like wheel E⁵ on the shaft B³ on which is a pinion E⁶ engaging a pinion E⁷ on a shaft E⁸ on which is a helical wheel E⁹ engaged by a like wheel E¹⁰ on what may be 15 considered the driving shaft E¹¹ of the machine. By this train of gearing is the roller B rotated.

The ductor-rollers C, D are carried in fixed brackets G the former alone being 20 driven by a helical wheel G¹ on its spindle which is driven by a helical wheel G² on a spindle G³ having on its lower end a like wheel G⁴ driven by a like wheel G⁵ on the shaft B³.

25 In operation and the roller B being in the position indicated by the chain-line circle its periphery is engaged by the adhesive-laden periphery of the ductor roller C. The two rollers rotate together in opposite directions 30 and the gearing is so set that the projection C¹ on the roller C enters (and so fills with adhesive) the groove B¹ in the roller B after the manner of the well known "Geneva" movement. The roller B having received a 35 coating of adhesive is now advanced to the book back, the projecting upper edge A² of which enters the groove B¹ and receives an adequate amount of adhesive therefrom. The roller B continues to rotate and the book

rises at the same speed from the position 40 shown in full lines in Fig. 2 to the position shown in dotted lines in said figure, the roller being pressed into contact with it by operation of the cam through the rack bar B⁸ so that it delivers its adhesive upon the side 45 of the book. It then retires to receive a fresh supply from the ductor roller C, the book is removed, another substituted and the cycle of operations recommences.

What I claim is:—

1. In book-binding machinery means for applying adhesive to the projecting edges and back of a book comprising an adhesive-applying roller on an axis parallel with the book and having a longitudinal groove substantially conforming in contour to the projecting edge, a ductor-roller serving the adhesive-roller and having a rib counterpart to the groove and means for moving book and roller into contact with one another and so 55 as to distribute adhesive from the roller over the edge and surface of the book, as set forth.

2. In the devices forming the subject-matter of the foregoing claim hereof means for advancing the adhesive roller to the book 60 and for moving the book across the path of the roller, as set forth.

3. In the devices forming the subject-matter of claim 1 hereof means for advancing the adhesive roller towards the book to apply 70 adhesive thereto and for retiring it into contact with a ductor roller to receive a fresh supply of adhesive and for driving the rollers in consonance as set forth.

In testimony whereof I have signed my 75 name to this specification.

JOHN MURRAY.
